UNITED STATES PATENT OFFICE.

GUSTAVE M. NELL AND WILLIAM G. KALE, OF CLEVELAND, OHIO, ASSIGNEES TO THE CLEVELAND ROCK DRILL COMPANY, OF CLEVELAND, OHIO.

DRILL-STEEL RETAINER.

Application filed June 18, 1923. Serial No. 646,032.

The present invention is directed to improvements in drill steel retainers for hammer rock drills.

The primary object of this invention is 5 to provide a device of this character so constructed that the same can be easily and quickly attached to or removed from the drill to permit renewal and reassembly of the various parts.

10 A further object of the invention is to provide a steel retainer constructed in such manner that strain and shocks on the parts are distributed in such a way as to decrease excessive wear and breakage.

15 It is a well known fact that devices of this kind are subjected to extremely hard usage and a resultant breakage of parts and this construction aims to permit the parts to be moved for replacement, and further 20 the parts are so related that the vibration of the drill positively cannot cause the parts to become accidentally disengaged.

With these and other objects in view, as will appear as the description proceeds, 25 the invention consists in the novel features of construction, combination of elements, and arrangement of parts, and hereinafter to be fully described and pointed out in the appended claims.

30 In the accompanying drawing:

Figure 1 is a side elevation of the device.

Figure 2 is a bottom plan view.

Figure 3 is a side elevation showing the steel retainer in a partially open position.

35 Figure 4 is a transverse sectional view.

Figure 5 is a sectional view on line 5—5 of Fig. 2.

Referring to the drawing 1 designates the front head of a drill, and in which is rotatably mounted the drill steel 2 having the usual collar 3 thereon, all of which are 40 of the usual construction.

Located upon the sides of the front head at diametrically opposite points are lugs 4, said lugs being out of alignment with the longitudinal axis of the front head and having their rear sides provided with flat faces 5, the purpose of which will appear later.

50 The retainer comprises a yoke 6 adapted to straddle the front head, the bight of which provides a loop 7, said loop serving to receive the steel 2. The rear ends of the side arms 8 of the yoke terminate in transverse heads 9, said heads having their rear

sides provided with centrally located curved seats 10 adapted to engage the forward round sides 11 of the lugs 4 for pivotal movement with respect thereto. These heads are provided with openings 12 in 60 which are slidably engaged paired bolts 13, the integral heads 14 thereof having faces 15, the purpose of which will later appear.

Pivotedly connected to one bolt 13 of each pair is a lock bar 16, the free end of which is provided with a hook 17 for detachable engagement with the adjacent bolt. It will of course be understood that these bars are prevented from disengaging the bolts in one direction by the heads 14, but can be conveniently placed thereon from the opposite ends. The inner faces of the bars 16 are provided with integral ribs 18 and 19, said ribs being arranged in obtuse angular relation with respect to the longitudinal axis 70 of the bars, whereby the respective ribs will lie in contact with certain faces 15 of the respective heads 14, when the bars are in their locked positions, thereby positively holding the bolts 13 against accidental rotation, as clearly shown in Fig. 4 in full lines.

The forward ends of the bolts 13 are threaded, as at 20, and are threaded in the ends of the connecting bars 21 which are 85 curved longitudinally to accommodate the side arms 8 of the yoke 6. Encircling each bolt 13 is a coil spring 22, and since these springs are interposed between the heads 9 and bars 21 the seats 10 and bars 16 will 90 yieldably engage the lugs 4 at diametrically opposite points.

The inherent resiliency of the yoke 6 is sufficient to cause the side arms 8 thereof to yieldably engage the recesses 23 formed 95 in opposite sides of the front head 1. These recesses serve in conjunction with the flat faces 5 as positive means to prevent the yoke from becoming accidentally opened as will be obvious. To open the retainer it is only 100 necessary to grasp the yoke and swing the same laterally until the bars 16 ride from the flat faces 5 of the lugs to the round sides 11 thereof, thus permitting the retainer to remain open until the drill steel has been 105 changed, after which retainer can be closed upon exerting slight stress thereon in a reverse direction or until the bars 16 return to the flat faces 5 and the side arms 8 snap into their respective recesses 23.

It will be obvious that when strain is applied to the yoke occasioned by the collar 3 engaging the loop 7, the yoke will naturally move longitudinally of the head 1 in a forward direction, and consequently the strain or shock will be absorbed by the springs 22.

To disassemble the retainer pressure is applied to the ends 20 of the bolts 13 or to the bars 21, as desired, whereupon the bolts 10 are slid rearwardly a sufficient distance to permit the locking faces 15 of the heads 14 to disengage the ribs 18-19, thereby permitting the bars 16 to be swung to their open positions, as shown in dotted lines in 15 Fig. 4 of the drawing. It is then necessary to swing the retainer to a position substantially at right angles to the front head so that the lugs 4 can pass between the heads 14 of the bolts 13, which can be readily accomplished owing to the presence of the flat faces 5. However, in order to accomplish this the heads 14 are turned so that certain of the locking faces 15 will be in direct alignment to provide a passage of sufficient width to permit the lugs pass therethrough. The manner of assembling the retainer will be readily apparent to those skilled in the art.

What is claimed is:

- 30 1. In combination with the front head of a rock drill having a collared drill steel operatively mounted therein, lugs upon opposite sides of the front head, a drill steel retainer comprising a yoke having a drill 35 steel engaging loop, the side arms of the yoke bearing against the front sides of the lugs, paired bolts slidable in the side arms and having heads, lock bars pivotally connected to one bolt of each pair and bearing against the rear sides of the lugs, means for holding the side arms and lock bars in yielding engagement with the lugs, and means carried by the lock bars for engaging the bolt heads, as and for the purpose set forth.
- 40 2. In combination with a front head of a rock drill and a collared drill steel rotatable therein, a drill steel retainer comprising a yoke having a steel engaging loop, headed bolts slidable in the side arms of the yoke, lock bars pivotally connected with certain of the bolts, means on the front head for pivotally connecting the rear end of the side arms and lock bars to the front head,

and means carried by the lock bars to engage the heads of the bolts to prevent accidental rotation thereof. 55

3. In combination with the front head of a rock drill and a collared drill steel rotatable therewith, lugs on the opposite sides of the front head, a drill steel retainer having a steel engaging loop and having its side arms pivotally engaged with the lugs, a pair of headed bolts slidable in each of the side arms, lock bars having one of their ends pivotally connected with one bolt of each pair and their other ends detachably engaged with the adjacent bolt, said lock bars being also pivotally engaged with the lugs, said lock bars having means thereon for engaging the head of the bolts of each 70 pair to prevent accidental rotation thereof, and means for yieldably holding the side arms and lock bars with the lugs. 65

4. In combination with a front head of a rock drill having a collared drill steel operating therein, lugs formed on each side of the front head, a drill steel retainer comprising a steel engaging yoke, the side arms of the yoke having heads on their rear ends for engaging the forward sides of the lugs, 80 a pair of headed bolts slidable in each head, bars connecting the forward ends of the bolts of each pair, lock bars having one of their ends pivotally engaged with a bolt of each pair and having their other ends provided 85 with hooks for detachably engaging the adjacent bolts, ribs carried by the lock bars for detachably engaging the heads of the bolts, and means carried by the bolts for holding the heads of the side arms and lock 90 bars in yielding engagement with the lugs. 95

5. In combination with the front head of a rock drill having a drill steel operatively engaged therein, lugs on the front head, a steel retainer comprising a yoke, the side arms of which are pivotally engaged with the lugs, a pair of spring restrained bolts slidably associated with the side arms of the yoke, and means pivotally engaged with one of the bolts of each pair for engaging both 100 bolts and each lug to prevent accidental rotation of said bolts.

In testimony whereof we have hereunto set our hands.

GUSTAVE M. NELL.
WILLIAM G. KALE.
